UNITED STATES PATENT OFFICE

162,269

COMBINATION RADIO PHONOGRAPH

Kurt H. Wittke, Berkley, Mich.

Application June 24, 1950, Serial No. 10,728

Term of patent 14 years

(Cl. D56—4)

To all whom it may concern:

Be it known that I, Kurt H. Wittke, a citizen of the United States, residing at Berkley, in the county of Oakland, State of Michigan, have invented a new, original, and ornamental Design for a Combination Radio Phonograph, of which the following is a specification, reference being had to the accompanying drawing, forming part thereof.

Fig. 1 is a front elevational view of a combination radio phonograph, showing my new design;

Fig. 2 is a fragmentary top plan view thereof;

Fig. 3 is a fragmentary sectional view taken on line 3—3 of Fig. 1.

The dominant features of my design reside in the parts shown by full lines in the drawing.

I claim:

The ornamental design for a combination radio phonograph, as shown and described.

KURT H. WITTKER.
